US00D683738S

(12) **United States Design Patent**
Wujcik et al.

(10) **Patent No.:** **US D683,738 S**
(45) **Date of Patent:** **** Jun. 4, 2013**

(54) **DISPLAY SCREEN WITH GRAPHICAL USER INTERFACE**

(75) Inventors: **Patrick Wujcik**, Issaquah, WA (US);
Kieran Phelan, Seattle, WA (US);
Michael H. LaManna, Kirkland, WA (US); **Priya Dandawate**, Seattle, WA (US); **Ken Hardy**, Redmond, WA (US)

(73) Assignee: **Microsoft Corporation**, Redmond, WA (US)

(**) Term: **14 Years**

(21) Appl. No.: **29/401,470**

(22) Filed: **Sep. 12, 2011**

(51) **LOC (9) Cl.** **14-04**

(52) **U.S. Cl.**

USPC **D14/485**

(58) **Field of Classification Search**

USPC **D14/485-495; 715/773, 753, 810, 715/769, 779, 766, 274, 751, 752, 740, 837, 715/786, 785; 709/203, 217**

(57) **CLAIM**

The ornamental design for a display screen with graphical user interface, as shown and described.

DESCRIPTION

The FIGURE is a front view of a display screen with graphical user interface showing the new design.

The broken line showing of the remainder of the user interface and of the display screen is for environmental purposes only and forms no part of the claimed design.

1 Claim, 1 Drawing Sheet
